(57) **CLAIM**

We claim the ornamental design for a beverage reservoir, as shown and described.

DESCRIPTION

FIG. 1 is a perspective view of the beverage reservoir;
 FIG. 2 is a top view thereof;
 FIG. 3 is a bottom view thereof;
 FIG. 4 is a front view thereof;
 FIG. 5 is a rear view thereof;
 FIG. 6 is a left side view thereof;
 FIG. 7 is a right side view thereof;
 FIG. 8 is a perspective view of a second embodiment of the beverage reservoir;
 FIG. 9 is a top view thereof;
 FIG. 10 is a bottom view thereof;
 FIG. 11 is a front view thereof;
 FIG. 12 is a rear view thereof;
 FIG. 13 is a left side view thereof; and,
 FIG. 14 is a right side view thereof.
 The broken lines in the figures are for illustrative purposes only and form no part of the claimed design.
